UNITED STATES PATENT OFFICE.

EVERET A. FLEMING, OF CHICAGO, ILLINOIS.

PASS OR TICKET FOR RAILWAYS AND THE LIKE.

1,171,420.

Specification of Letters Patent. Patented Feb. 15, 1916.

Application filed October 14, 1912. Serial No. 725,740.

To all whom it may concern:

Be it known that I, EVERET A. FLEMING, a citizen of the United States, and a resident of Chicago, county of Cook, and State of Illinois, have invented a certain new and useful Pass or Ticket for Railways and the like, of which the following is a full, clear, and exact description.

The invention relates to passes or tickets for railways, steamboats and the like, but more particularly to a free transportation ticket or pass.

The invention seeks to provide an improved form of ticket or pass in which the ticket or pass proper, coupons therefor and a record of the ticket or pass may be made out at a single writing, and which provides safeguards against improper use.

The invention consists in the features of improvement hereinafter set forth, illustrated in the preferred form in the accompanying drawings and more particularly pointed out in the appended claims.

In the drawings, Figure 1 is a view of the obverse face of the improved ticket or pass and Fig. 2 is a view of the reverse face thereof.

The ticket or pass is formed of a paper strip which is divided by weakened vertical lines 1 and 2 into three sections of substantially equal size. The end sections D and C form respectively the pass or ticket proper and a record coupon which, after the pass or ticket is made out, is detached and filed with the proper official of the railroad.

The central section is further divided along the weakened line 3 into two detachable coupons A and B of substantially equal size. If desired, a narrow section E is provided at one end and is connected to the record or coupon C along a weakened vertical line 4. Section E forms a margin by which a number of the blank forms may be bound together into a book. In the preferred form shown, section D forming the pass or ticket proper is somewhat longer than the other two sections and is provided with an end portion F, which, on the obverse face, is divided from the main portion of the pass by a vertical line 5.

Each ticket or pass has a serial number which is printed upon each of the sections C and D and upon each of the half sections A and B. In the particular ticket shown, this serial number "F-21207" is printed

upon the obverse face of each of the sections A, B, C and D. The end sections C and D and the central section also bear appropriately designated spaces 6 for the name of the holder of the pass or ticket, 60 and, preferably, also, for his address, and the name of the party or concern on whose account or at whose request the pass or ticket is issued. The end and central sections also bear on their left-hand portions 65 appropriately designated spaces 7 for receiving data concerning the going trip and upon their right-hand portions, appropriately designated spaces 8 for receiving data concerning the return trip. Preferably, also, these sections, beneath the spaces 70 7 and 8, have appropriately designated spaces 9 and 10 for receiving the date of issue and the date upon which the pass or ticket expires or becomes void.

The designated spaces 6, 7, 8, 9 and 10, on the three sections of the pass or tickets are located alternately upon the opposite faces of the strip. In the particular form shown, these designations appear upon the obverse faces of the end sections C and D, and upon the reverse face of the central section forming the coupons A and B, so that, when the sections are folded upon the lines 1 and 2 and superposed, the spaces will 80 be in register and, by placing sheets of carbon paper between the sections, the data upon all of these spaces upon the separate sections can be filled in at a single writing. 85 If we assume the ticket to be in the position shown in Fig. 1, it is folded for filling out as follows: The portions on the left of the line 2 are folded over to the right to bring the central section on to the obverse face of the end section C. The end section 90 D is then folded to the left about the line 1 to bring it on to the reverse face of the central section. The spaces 6, 7, 8, 9 and 10 upon the three sections will then register so that, as stated, they can be filled out at 95 a single writing. Heretofore, free transportation tickets or pass forms have been usually so arranged that it was necessary to fill out two separate forms, one for the going trip and one for the return trip and, 100 also, to preserve a record, to fill out a coupon or stub to which the going and return trip forms were detachably connected. With the present form one writing suffices. 105 It also permits the use of a typewriter for 110

the complete operation of issuing a pass or ticket and does away with separate pen stubbing.

The section D preferably bears upon its obverse face an appropriately designated space 11 for the signature of the official countersigning or validating the pass or ticket, and the record coupon in the form shown bears appropriately designated spaces 12 and 13 for the names of the official issuing the pass and of the party or concern requesting the same. On its reverse face the record coupon or section C, in the form shown, bears instructions in regard to the manner of issuing the pass or ticket. After it has been made out, the record coupon C is detached and is sent to the recording office, preferably with the authorization or request for the issuance of the pass or ticket, and the coupons so received are filed at the recording office in numerical order. This permits a prompt examination of an exact copy of the pass by the recording office and also of the request or authority for its issue and, in most cases, before the pass or ticket proper is presented for passage. Any improper issuance of the pass can thus be detected and the pass can usually be canceled before it is used, and certainly before it is entirely used. Under the present practice, the stubs, which contain copies of the passes issued, are not turned into the recording office until the entire stub book is filled.

The half sections or coupons A and B preferably bear upon their reverse faces appropriately designated spaces 14, 15 and 16 for receiving data concerning the train, date and the conductor of the train upon which the pass is first presented for the going and return trips. The half section or coupon A is intended to be taken up by the first conductor to whom the pass or ticket is presented on the going trip. In the preferred form shown, it bears upon its obverse face appropriately designated spaces 17 for the signature and address of the user, whereby he acknowledges receipt of the pass and certifies that he is the person legally entitled to its use. This acknowledgement and certificate or coupon A is taken up by the first conductor to whom the pass is presented for passage and is turned in to the recording office, where it is filed with the copy of the pass appearing upon record coupon C already received from the issuing office. When coupon A is thus filed, a comparison can be easily made between it and coupon C and any irregularity in the use of the pass thus detected and, if necessary, steps may be taken to cancel the pass. With the form of pass now commonly in use, it may be improperly issued to one party and stubbed for another. If the pass is then used short of the destination, it will not be collected by the conductor and will not be turned in, so

that the evidence that it was issued to one party and stubbed to another is destroyed. With the present form the coupon A is taken up by the first conductor to whom the pass is presented upon the going trip and is filed with the recording office so that such improper use will be prevented. Furthermore, when the first conductor handling the pass detaches coupon A, the copy of the pass appearing upon the reverse faces of the coupons A and B and the name of the holder thereon is torn in half, thus insuring against any attempt to afterward change the pass to include or cover other than the party first named at the time of issuance. This prevents any improper manipulation of the pass on the return trip.

The half section or coupon B also bears upon its obverse face appropriately designated spaces 18 for the signature and address of the user. This coupon is taken up by the first conductor to whom the pass or ticket is presented on the return trip and is turned in and filed in the recording office, so that abuse of the pass upon the return trip is guarded against.

In case any stop-over is permitted, it is always after either or both of the coupons A and B are collected. The holder will be required to sign a regular form of identification slip when the pass is first presented to the conductor after a stop-over. These slips are turned in and filed in the recording office with the portions of the pass already collected. A comparison of the signatures will readily disclose whether or not the pass has changed hands during the stop-over and if it has, the original holder can be called to account.

In case the pass or ticket is issued for one way only, the return trip portion upon the pass proper or section D and upon the coupons B and C will be crossed out, or the words "One way only" written across the same. When a one-way pass is presented, the conductor first handling the same will take up both the coupons A and B and return them together. Should he fail to do this, or should the pass have been changed before it is presented for passage, the fact will become known immediately upon receipt of the coupon A in the recording office and it may then be immediately bulletined for canceling its use for a return trip. At the end of the trip, the section D forming the pass or ticket proper is taken up and turned in and filed with the recording office. For the purpose of investigating any irregularity, the recording office has, upon coupon C, the name of the party issuing the pass, the name and address of the party to whom it is issued, and upon coupon A, when turned in, the signature and address of the party presenting the pass for passage. If any irregularity appears, the origi-

nal holder of the pass or the party issuing the same, can be called to account and the fact that any abuse is readily discovered, will act as a preventive against improper use.

5 The reverse face of the pass or ticket proper, formed by the section D, preferably has suitably designated spaces 19 for the signature and address of the holder, which 10 are placed below the usual restrictions pertaining to the extent of liability of the railroad. It also has, in the form shown, suitably designated spaces 20 which are punched by the successive conductors to 15 whom the pass is presented upon the going and return trips. Upon its obverse face, the portion F may bear any restriction desired as to the manner in which the pass or ticket may be used and, in the form shown, 20 it has appropriately designated spaces 21 on its reverse face for receiving data pertaining to any stop-overs permitted.

It is obvious that the improved pass or ticket may be adapted, not only for going 25 and return trips, but also for separate trips or the separate sections of a journey and that other changes may be made in the details set forth without departure from the essentials of the invention as defined in the 30 claims.

I claim as my invention:

1. A pass or ticket comprising a strip divided by vertical lines into three sections, each provided with appropriately designated 35 spaces to receive data concerning the going and return trips, located respectively on separate portions thereof, said designated spaces appearing on the obverse faces of the end sections and on the reverse face 40 of the central section and registering when the sections are superposed, said end sections forming respectively the pass or ticket proper and a record coupon, and the going and return trip portions of said central section being divided to form separate identification coupons, substantially as described.

2. A pass or ticket comprising a strip divided by weakened vertical lines into three substantially equal sections, each provided with appropriately designated spaces 50 for receiving data concerning the holder of the pass or ticket and each section having appropriately designated spaces to receive data concerning the going and return trips on its right and left hand portions, respectively, said designated spaces appearing alternately on the opposite faces of said sections and registering when the sections are folded upon one another, said end sections 55 forming respectively the pass or ticket proper and a detachable record coupon and the right and left hand portions of said central section being divided by a weakened vertical line to form detachable identification 60 coupons, substantially as described.

3. A pass or ticket comprising a pass or ticket section and a coupon section, each of said sections having appropriately designated spaces for receiving data concerning the holder and the going and return trips, 70 said coupon section being divisible into two detachable coupons bearing respectively said designated spaces for the going and return trips and each having an appropriately designated space for the signature of the user of the pass or ticket, said pass or ticket section and each of said coupons bearing the same serial number, substantially as described.

4. A pass or ticket comprising a strip 80 divided by vertical lines into three substantially equal sections, each having appropriately designated spaces for receiving data concerning the holder of the pass and the going and return trips, said designated spaces being located on the obverse face of the end sections and the reverse face of said central sections and registering when said sections are superposed, said designations for the going and return trips being located on the right and left hand portions respectively of each of said sections, and the right and left hand portions of said central sections being divided by a vertical line to form separate detachable coupons, each of 85 said coupons having an appropriately designated space for the signature of the user of the pass, and said coupons and said end sections each bearing the same serial number, substantially as described.

5. A pass or ticket comprising a strip divided into a plurality of sections, each provided with appropriately designated spaces to receive data concerning separate trips arranged to register when said sections are superposed, said designated spaces for the separate trips being arranged, respectively, on separate portions of each of said sections, and the said separate portions of one of said sections being divided to form 105 a plurality of separately detachable identification coupons, each bearing the designated spaces pertaining to one trip, substantially as described.

6. A pass or ticket comprising a pass or ticket section, a coupon section and a record section, each of said sections having appropriately designated spaces for receiving data concerning the person of the holder of the pass or ticket and having appropriately designated spaces on separate portions thereof for receiving data concerning separate trips, the said separate portions of said coupon section being divisible into a plurality of separately detachable, identification 115 coupons, each bearing said designated spaces pertaining to one trip, substantially as described.

7. A pass or ticket comprising a strip divided by weakened lines into a plurality 130

of substantially equal sections each having appropriately designated spaces for receiving data concerning the holder of the pass and each section having appropriately designated spaces upon separate portions thereof for receiving data concerning separate trips, said designated spaces being arranged to register when said sections are superposed, the said separate portions of said coupon section being divided by weakened lines to form a plurality of separately detachable, identification coupons each bearing

10 Copies of this patent may be obtained for five cents each, by addressing the "Commissioner of Patents, Washington, D. C."

ing the said designated spaces pertaining to one of the trips and each coupon having an appropriately designated space for the signature of the user of the pass or ticket, said sections and each of said coupons bearing the same serial number, substantially as described. 15
